Specification for Design.

Patented May 13, 1913.

Application filed November 11, 1912. Serial No. 730,820. Term of patent 14 years.

To all whom it may concern:

Be it known that I, ARTHUR L. GARFORD, a citizen of the United States, residing at Elyria, in the county of Lorain and State of Ohio, have invented a new, original, and ornamental Design for the Rear Fenders for Automobiles, of which the following is a specification, reference being had to the accompanying drawing, forming part thereof.

In the drawing, Figure 1 is a side eleva-

tion, Fig. 2 a plan, and Fig. 3 a rear end elevation of a fender showing my new design.

I claim:

The ornamental design for a rear fender for automobiles, substantially as shown.

ARTHUR L. GARFORD.
